(57) **CLAIM**

The ornamental design for a flapped shower curtain liner, as shown and described.

DESCRIPTION

FIG. 1 is a rear view of the flapped shower curtain liner, with a portion of unclaimed environmental structure shown; FIG. 2 is a front view of the flapped shower curtain liner, with a portion of unclaimed environmental structure shown; FIG. 3 is a rear view of the flapped shower curtain liner, with a portion of unclaimed environmental structure shown; FIG. 4 is a front view of the flapped shower curtain liner, with a portion of unclaimed environmental structure shown; FIG. 5 is a side angled prospective view of the flapped shower curtain liner, with a portion of unclaimed environmental structure shown; and, FIG. 6 is an opposite side angled prospective view of the flapped shower curtain liner, with a portion of unclaimed environmental structure shown. The broken lines shown in the drawings represent environmental structure and/or unclaimed portions of the flapped shower curtain liner, and form no part of the claimed design.
